UNITED STATES PATENT OFFICE.

C. SHALER SMITH, C. H. LATROBE, AND FREDERICK H. SMITH, OF BALTIMORE, MARYLAND.

IMPROVEMENT IN CONSTRUCTION OF BRIDGES.

Specification forming part of Letters Patent No. 97,975, dated December 14, 1869.

To whom it may concern:

Be it known that we, C. SHALER SMITH, C. H. LATROBE, and FREDERICK H. SMITH, of Baltimore, county of Baltimore, and State of Maryland, have invented certain new and useful Improvements in Bridges; and we hereby declare the following to be a full, clear, and exact description of the same, reference being had to the accompanying drawing, in which—

Figure 1 is a side elevation of a trestle-bridge made in accordance with our invention. Fig. 2 is a transverse section of the same. Figs. 3, 4, 5, and 6 are views on an enlarged scale of detached parts.

Our invention may be stated to consist in, first, the use, in a system of wrought-iron piers or continuous trestle, composed of wrought-iron columns combined with cast-iron joint-boxes interposed between and forming the bearings of the sections of the columns, as hereinafter described, of longitudinal diagonal ties which shall connect the joints of any one tier with those of another tier or with the caps or feet of the columns forming the piers, and the attachment of these ties directly to the columns themselves or to the cast joints, caps, or feet, or to the longitudinal struts, as may be best in different locations; second, the combination, with the piers and system of longitudinal diagonal ties connecting the same, of the wooden chord-sticks and longitudinal system of wooden struts for supporting the roadway and stiffening the piers; third, the construction of the cast-iron post-caps, foot-boxes, and joint-boxes for the wrought-iron columns, substantially as hereinafter shown and described; fourth, the combination of a series of independent or isolated bridge-piers, formed, as described, with an intermediate span or spans of truss connecting the same, substantially as hereinafter set forth; fifth, uniting the longitudinal diagonal ties with the columns or boxes of said columns by means of a yoke and screw-nut attachment, such as hereinafter described, so as to admit of the ready adjustment of said ties; sixth, a system of continuous trestle for bridges in which the longitudinal diagonal rods or ties which connect the caps and feet or joints of the columns

are combined with intermediate spans of truss extending between said columns.

To enable others skilled in the art to understand and use our invention, we will now proceed to describe the manner in which the same is or may be carried into effect, by reference to accompanying drawing.

1. *The Construction of the Piers.*

These parts are formed of columns or shafts of wrought iron or steel of any form of section, which, as shown in Fig. 6, fit over tenons formed on the cast-iron foot-boxes F. These foot-boxes are bolted or otherwise suitably anchored to masonry, and to them are pinned or pivoted the straps or yokes which receive the lower ends of the longitudinal diagonal ties 4. Running through the castings and secured thereto by bolts are the transverse struts S³, formed each of two channel-bars or their equivalents for the purpose, between which the lateral ties 2 are hung. The upper end of each column fits over a tenon formed on the cast-iron post-cap C, Fig. 4, this cap being adapted to receive and hold the chord-sticks, the cross-struts, the truss-chains, and the longitudinal diagonal ties. The chord-sticks are framed in pairs to the cap, one on each side of the rib that extends across its top, and on each side of which are placed the plates or bars which run through the cap and form the jaws between which the longitudinal diagonal ties take hold of the cap. These bars are held in place by the pin upon which the truss-chains are hung, the pin passing through the hole formed for its reception in the cap, as represented in Fig. 4.

The construction and arrangement of the cross-strut S¹ in nowise differs from that of the strut S³ already mentioned. The lateral ties 1 also take hold of the cap in the manner already described with reference to the lateral ties 2.

To unite the column with its cap and foot, all that is required is to slip its ends over the tenons formed on the foot-box and cap, so that the pier can be set up with great ease and expedition.

To construct the piers of considerable height we form them in tiers or stories, and to this end

we make use of cast-iron joint-boxes, such as represented in Fig. 5. This joint-box, which is interposed between and forms the bearing for the contiguous ends of the sections to be united, has a tenon on each end, over which fits the upper end of the lower section and the lower end of the upper section, to be joined in one continuous pier; as, for instance, in Fig. 1 the center piers are made in three stories or tiers, A B, B C, C D, thus necessitating the employment of a foot-box, cap, and two joint boxes. The lower column C D, fits over the tenon of foot-box and the lower tenon of the first joint-box. The middle column B C fits over the upper tenon of the first, and the lower tenon of the second joint-box, and so on.

This method of uniting the sections combines in itself strength and ease in fitting the parts together. The contiguous ends of the wrought-iron sections, united by the joint-boxes, have no contact with each other, but take a direct bearing on the boxes themselves, and the structure can be set up with great rapidity and facility.

The cross-strut S^2 , made of channel-bars, is secured in the joint-box, in the manner already indicated, with reference to the struts S^1 S^3 , and from between the channel-bars the lateral ties 1 2 extend in the usual manner.

The two longitudinal tie rods or stays 4 which meet or cross each other on the same side of the joint-box, have their straps hung upon the same pin, as shown in the figure. We stiffen the piers at their joints by means of a system of longitudinal struts, X, which are anchored or abut against masonry or its equivalent at each end of the bridge, and fit into the joint-boxes, as seen in Fig. 5. In a continuous trestle-work we prefer, and, in fact, find it quite necessary, to make these struts, as well as the chord-sticks, of wood, in order to prevent the contraction and expansion consequent upon the employment of an iron-strut system.

In illustration of our invention we have described the method we prefer of constructing the cast-iron caps, feet, and joints, and of uniting them with their wrought-iron columns. The construction of these parts may, however, be varied to a great extent according as circumstances require; and, so far as the method of uniting the parts is concerned, the columns may fit over the caps, feet, and joints, or the latter may fit over the former, or the two may be riveted or bolted together, as may be found necessary in using different sections of columns.

In all cases, however, we obtain piers formed of shafts or columns of wrought-iron or steel, with feet, caps, and joints, where the same are employed, of cast-iron.

2. The Longitudinal Diagonal Tie System.

The manner in which these ties 3 4 can be used is shown in diagram in Fig. 1. The upper end of one stay, in this instance, is anchored to

the top of one pier or post, and thence it extends diagonally downward, and is anchored to the foot of the second, third, or further pier beyond, passing through and being united with the joint-boxes of the intermediate columns.

The manner in which the ties 4 are united with the columns which they intersect is shown clearly in Fig. 5. Their ends pass through yokes or jaws pivoted to the boxes, and are there held by means of screw-nuts, by which the ties can be tightened and readily adjusted, this being a matter of some importance, as in bridges built upon this system the metal is affected by the variation in temperature, and the parts require, therefore, to be adjusted to compensate for whatever contraction or expansion may take place. By this means, although less material is employed in the tension members, the piers are nevertheless just as well or even better adapted to resist the strain than with the ordinary system of bracing, which will require a much greater amount of material. The whole structure, in fact, is united in one continuous system, each part supporting and upholding the other.

This system of tie-rods is represented as continuous from the cap of one column to the base of another; but it can also be used with just as good effect to connect the joints of one tier with those of another tier, or with the caps or feet of the columns forming the piers; and while we find it convenient and best on many accounts to attach the ties to the feet, caps, and joint-boxes in the manner already described, yet they may be also attached directly to the columns themselves, or to the longitudinal struts, as may be best in different locations, without departing from the principle of our invention.

The mode above described is adapted more particularly to the crossing of dry ravines or valleys where there is no stream of any considerable size to be bridged; but in case a large body of water must be spanned, or other circumstances make it inconvenient or impracticable to employ a continuous trestle-work, we contemplate the construction of independent piers upon the same general plan, which can be connected by one or more channel-spans. For instance, suppose that the three center bents of the structure, shown in Fig. 1, were removed, thus leaving the independent piers; between these two piers a channel-span, composed of any suitable form of truss, should be introduced, and, by counterbracing the end bents of the two piers, a perfectly safe and strong bridge would be produced.

When the piers are thus constructed it is not necessary that the longitudinal stays should be anchored to the foot of any one column, but they may extend from the cap of one post to any point on the second or further post beyond intermediate between the cap and base, being united, of course, with the intermediate column or columns, as above described.

In the bridge represented in illustration of our invention, the piers or columns are set at such a distance as to require the use of a truss; but of course the posts can be set at any required distance apart, so as to dispense, if need be, with the truss.

The combined use of the intermediate spans and longitudinal ties with the piers, as shown in Fig. 1, is, however, productive of great advantage; for a strong and durable structure is obtained, while at the same time we are enabled to set the posts or columns at a greater distance apart than has heretofore been found practicable; and, so far as this portion of our invention is concerned, the particular construction of the columns or posts is immaterial, though we prefer the construction hereinbefore described. In place of the channel-bars or iron of equivalent form inserted in the boxes or caps, and used for the cross-struts, we have employed small columns which fit over tenons cast on the sides of the joint-boxes, foot-boxes, or caps with which the struts require to be connected.

Having now described our invention, and the manner in which the same is or may be carried into effect, we would say that we do not here claim the combination of wrought-iron column with cast-iron caps, feet, or joints, when used to form either independent piers or a connected trestle, as this feature we have made the subject of a separate application for Letters Patent; but what we now claim, and desire to secure by Letters Patent, is—

1. In a system of wrought-iron piers or continuous trestle, such as described, the combination, with the cast-iron joint-boxes interposed between and forming the bearings for the column-sections, of longitudinal diagonal ties, connecting, substantially in the man-

ner specified, the joints of any one tier with those of another tier, or with the caps or feet of the columns, for the purposes set forth.

2. The combination, with the piers and system of longitudinal diagonal ties connecting the same, of the wooden chord-sticks and longitudinal system of wooden struts for supporting the roadway and stiffening the piers.

3. The construction of the cast-iron posts, caps, foot-boxes, and joint-boxes, substantially as shown and described.

4. The combination of a series of independent or isolated bridge-piers, formed, as described, with an intermediate span or spans of truss connecting the same, substantially as set forth.

5. Uniting the longitudinal diagonal ties with the columns or boxes of said columns by means of the yoke and screw-nut attachment, substantially as shown and described, so as to admit of the ready adjustment of said ties, for the purposes stated.

6. A system of continuous trestle for bridges in which the longitudinal diagonal rods or ties which connect the caps and feet or joints of the columns are combined with intermediate spans of truss extending between said columns, substantially as shown and set forth.

In testimony whereof we have signed our names to this specification before two subscribing witnesses.
